UNITED STATES PATENT OFFICE

EDWARD MROSS, OF RACINE, WISCONSIN, ASSIGNOR TO HAMILTON BEACH MFG. CO., OF RACINE, WISCONSIN, A CORPORATION OF WISCONSIN

VACUUM-CLEANER-HANDLE MOUNTING

Application filed October 31, 1928. Serial No. 316,333.

This invention relates to handle mountings, and more particularly to means for mounting a handle on the body of a vacuum cleaner.

5 The main object of the invention is to provide an inexpensive and efficient means for removably mounting a handle upon a vacuum cleaner in such manner that the handle may be moved freely when in use and may be held in a stationary vertical or horizontal position when desired.

Another object is to provide a mounting which will cooperate with the handle to permit the cleaner to be bodily lifted, by means 15 of the handle, to a raised position, as may be required when cleaning stair carpets.

In the drawings:

Figure 1 is a side elevation of a vacuum cleaner embodying my invention, the handle 20 and dust bag being broken away.

Figure 2 is a sectional view taken on the line 2—2 of Figure 1, looking in the direction indicated by the arrows.

Figure 3 is a perspective view of the 25 bracket comprising part of the handle mounting.

The following is a general description of the vacuum cleaner to which my invention has been applied. The body of the cleaner 30 comprises a motor housing 15, substantially round, in transverse, vertical cross section, partially closed at its rear end 16, and provided with an outwardly extending flange 17 at its forward end. Ventilating openings in 35 the housing 15 are indicated at 15'. Connected to said flange 17 by screws 18 is a fan casing 19, so arranged that the fan (not shown) will be in axial alignment with the motor shaft. A suction nozzle 20, terminating in a suction mouth 21, is preferably integral with and extends forwardly and downwardly from the fan casing 19. The front wall 22 of the nozzle 20 has an opening therethrough which is substantially in 40 alignment with the axis of the fan, and said

opening is normally closed by a removable plate 23. This opening in the wall 22 is provided for the purpose of accommodating a coupling (not shown) for an auxiliary suction tool which may be connected to a flange 50 on the inner surface of the fan casing in such manner that communication between the fan chamber and suction mouth 21 is cut off, and communication established between the auxiliary tool and said fan chamber. Not being 55 a part of this invention, this auxiliary tool connection to the fan casing need not be described in detail.

The body of the cleaner is supported at the rear upon a roller 24 and near the forward end by a pair of rotatably mounted wheels 25. A stationary brush 26 is removably mounted externally of the nozzle 20 by means of a bracket 27. A handle 28, having bifurcated ends or spring arms 29 adapted to engage the sides of the motor housing 15, is removably and pivotally mounted on pins 30 which extend outwardly from the sides of the said casing 15. The electric current wire 31 connects the motor with a source of power 60 through an extension cord usually carried on the handle 28. The fan casing 19 has the usual tubular extension 32, to which a dust bag 33 is removably secured.

Referring now more particularly to the 65 features of construction sought to be protected hereby, it will be noted that the handle 28, when not being manipulated by the operator, may be maintained in stationary vertical or horizontal position by a bracket indicated as a whole at 34. The dotted lines on Figure 1 indicate these positions.

This bracket 34 comprises a plate 35, apertured at 36 to fit over one of the pins 30 on the motor housing 15. The plate 35 will be 80 substantially vertically disposed and will contact with one side of the housing 15. An angularly extending portion 37, integral with the plate 35, is adapted to fit against the flange 17 of the casing 15, and is connected 85 90

thereto by the screw 38. The bracket 34 is first secured to the housing, as stated, and then the spring arms 29 of the handle 28 are slightly spread apart and snapped into position upon the pins 30, where the tension of the metal will hold one arm against the casing 15 and the other arm 29 against the bracket 34.

At the lower margin of the plate 35, between the aperture 36 and that side margin toward the rear, is a horizontally disposed, outwardly extending ear 39 upon which the arm 29 rests when the handle 28 is allowed to drop to horizontal position. This ear 39 acts as a stop to prevent the arm from dropping below horizontal position, and is particularly useful when it is desired to lift the cleaner as a whole by means of the handle to a raised surface, as is required when cleaning 20 stair carpets.

The upper portion of the plate 35, toward its forward side margin, is provided with a spring clip 40, preferably integral with the plate 35, for the purpose of engaging the arm 29 of the handle between said clip 40 and the outer surface of the plate 35 when it is desired to maintain the handle 28 in a vertical position.

The construction described provides a simple, inexpensive and efficient means of maintaining the handle 28 in a stationary vertical position where it may be conveniently grasped by the operator when resuming the use of the machine, as well as a convenient means for 35 holding the handle in stationary horizontal position, and for cooperating with the handle when the handle is used as a lever for lifting the cleaner to a raised surface.

Obviously, changes in details of construction may be made without departing from the scope of my invention, and I do not intend to be limited to the precise form shown and described, except as pointed out in the appended claims.

45 I claim as my invention:

1. A vacuum cleaner having a horizontally disposed pin extending outwardly from each side of the cleaner body, a bracket secured to said body adjacent one of said pins, said bracket consisting of a substantially flat apertured plate member having an outwardly extending, horizontally disposed ear on its lower margin, rearwardly of the aperture in the plate, said pin extending through the 55 aperture of the plate, and a handle having bifurcated arms apertured at their lower ends and pivotally mounted on said pins on the cleaner body in engagement with the outer surface of the bracket.

60 2. In a vacuum cleaner having a motor casing, a fan casing located forwardly of the motor casing, and a pin extending horizontally outwardly from each side of the motor casing, a bracket consisting of two integral 65 plate members angularly disposed relative to

each other, one of said plate members being secured to the fan casing and the other being apertured and located adjacent the motor casing, one of the pins on the motor casing extending through the apertured plate member, a handle having spaced apart arms pivotally mounted on said pins, and means on the bracket for limiting the movement of the handle arms.

In testimony, that I claim the foregoing 75 as my sole invention, I affix my signature, this 22d day of October, 1928.

EDWARD MROSS.
